UNITED STATES PATENT OFFICE

109,825

DESIGN FOR A BILLIARD TABLE

Charles A. Wendt, Milwaukee, Wis.

Application March 7, 1938, Serial No. 75,651

Term of patent 7 years

To all whom it may concern:

Be it known that I, Charles A. Wendt, a citizen of the United States, of Milwaukee, in the county of Milwaukee and State of Wisconsin, have invented a new, original, and ornamental Design for a Billiard Table, of which the following is a specification, reference being had to the accompanying drawing, forming part thereof.

The figure is a perspective view of a billiard table showing my new design.

I claim:

The ornamental design for a billiard table, as shown.

CHARLES A. WENDT.
